Primary Examiner — Cathron C Brooks*Assistant Examiner* — Ian F Whitmore(74) *Attorney, Agent, or Firm* — Wegman, Hessler & Vanderburg**CLAIM**

The ornamental design for a display screen or portion thereof with icon, as shown and described.

DESCRIPTION

FIG. 1 is a front view of a display screen or portion thereof with icon showing my new design; and,

FIG. 2 is a front view of a second embodiment thereof. The rectangular broken-line perimeter illustrates a display screen or portion thereof and forms no part of the claimed design. The remaining broken lines illustrate portions of an icon and form no part of the claimed design.
